SAFETY STRIKING MATCH

Eli E. Penter, Huntington Park, Calif.

Application November 27, 1940, Serial No. 367,347

6 Claims. (Cl. 44—45)

The present invention relates generally to what are commonly known as safety matches, and more particularly to what I have termed a safety striking match, as an improvement upon the generally used safety match involving the rubbing action of an igniting compound or material on the match splint against a special abrasive compound or material on the box or cover, it being the primary object of the invention to provide a match which may be ignited by striking the same endwise against any solid or suitably resistant surface, with safety in so doing, both as regards the surface struck, and the holder of the match.

It is well known that of the two types of matches now in general use, the one which may be ignited by rubbing against any dry surface capable of providing sufficient friction, cannot be used in many instances where the only dry surfaces immediately available would be damaged by its rubbing thereon and the fact that ignition initially takes place at the point of friction.

The other general type, known as a safety match, must be rubbed against a special abrasive material or compound on the match box or pad, and the disadvantage of this match is that it requires the use of both hands, one to hold the match and one to hold the box or pad.

It is my purpose to provide a match which may be struck, without the necessity of any rubbing action, against any suitable or available surface capable of resistance to a direct blow, and ignited by the use of only the hand holding the match, and without damage to the surface struck, or danger to the holder of the match.

It is a further object, for the above purposes, to provide a match which may be ignited by a single hand operation projecting the same endwise against a resistant surface, and will initially develop ignition at a point remote from both the hand holding the match, and the surface against which it is projected.

It is still another object, in the interest of safety in carrying or transporting the matches, to provide for the above in an arrangement in which the ignition material and the abrasive or friction material are, prior to actual striking of the match in use, safely maintained out of possible contact and, in this sense, remotely disposed relative to each other.

With the above general outline of the invention, its further objects and advantages may be better understood and more thoroughly appreciated in the course of the following detailed description of certain practical exemplifications of

the same, and by reference to the accompanying illustrative drawing, which forms a part of this specification, and in which,

Figure 1 is a view illustrating the practical manner of use of the match proposed by this invention.

Figure 2 is a perspective view of the match, the abrasive holder or finger piece being cut and opened.

10 Figure 3 is a side view, with the abrasive holder in vertical, longitudinal section.

Figure 4 is an edge view with the abrasive holder in vertical, longitudinal section.

Figure 5 is an enlarged fragmentary sectional view showing the coacting portions of the ignition train and the abrasive holder.

Figure 6 is an edge view in elevation of a match constituting a slightly modified form of the invention.

20 Figure 7 is a similar view showing the abrasive holder of Figure 6 in section and in igniting position during use of the match, and,

Figure 8 is an enlarged cross section through the match taken substantially on line 8—8 of Figure 7.

Referring now particularly to Figures 1 to 5 inclusive, I propose a match consisting of a splint 10 which is preferably rectangular in cross section and which may be made of any suitable material capable of sustaining the same against a quick, sharp endwise impact against a resistant surface.

At one end, the splint 10 is coated, or otherwise provided, with a head of ignition material indicated at 11, and a train of such material, as indicated at 12, is provided lengthwise of, and partially along, the splint 10, from the head 11 to a point intermediate the ends of the splint substantially remote from the head. This ignition train 12, whose outer end joins the main ignition head 11, preferably terminates at its opposite or inner end in a nodular extremity 13.

Sleeved on the opposite end portion of the splint 10 is a tubular abrasive holder or finger piece 14, preferably snugly, though slidably, embracing the splint, with a tightly closed outer end, as by means of a suitably fixed internal plug 15 which limits movement of the holder or finger piece 14 in the direction of the ignition head or end of the splint.

Within one side of the inner end of the holder 14 it is provided with an abrasive compound or material 16 coated thereon or otherwise fixed thereto, and in the assembly of the holder on the splint, the former is telescoped on the splint with

its abrasive 16 at the same side as the ignition train 12, and is fixed with respect to the splint with its inner end spaced lengthwise of the latter with respect to the inner end or nodule 13 of the ignition train. This is accomplished by readily frangible means as for instance glue or other suitable adhesive 17, see Figures 4 and 5, at the opposite side of the splint, the outer closed end 15 of the holder 14 being at this time spaced from the corresponding enclosed end of the splint 10.

As thus assembled, the telescoping abrasive holder, which as above suggested constitutes the hand or finger piece of the match, is held apart from the ignition train in a manner to clearly and safely avoid the danger of premature ignition and to require that the match, grasped in the fingers of one hand by its holder 14, be struck for ignition purposes endwise against a resistant surface, as plainly seen in Figure 1. The striking, as against such a surface, merely requires a quick, sharp impact at a single point, without rubbing, and may be imposed on a polished surface without danger of marring or marking the same, since it is only necessary that the frangible anchorage of the holder at 17 be broken to permit the latter to be shifted for its limited movement lengthwise of the splint toward the ignition head of the latter.

During the above movement of the holder relative to the splint, the abrasive material 16 rubs over the nodule 13 at the inner end of the ignition train 12, and initially affects ignition, which it will be noted is at a point substantially remote from the fingers as well as from the striking surface, or in other words the striking end of the splint. The match is then removed from the striking surface immediately following its natural rebound therefrom and is safely at a considerable distance therefrom by the time the flame has traveled along the ignition train to the ignition head 11 where the flame is increased to a point capable of promoting ignition of the splint itself.

By the above means, and in the above manner, the striking of the match is accomplished with the use of one hand only, and with complete safety to the hand as well as to the surface against which the match is struck.

By reference to Figures 6 to 8 inclusive it will be noted that the ignition head 11^a may be located at a point spaced from the striking end 18 of the splint 10^a so that in striking the match no portion of the ignition material will come into contact with the surface against which the splint end 18 impacts. Thus it will be possible to safely use the match against a table surface covered by a table cloth without danger of staining the cloth with a color spot at the point of contact, which might result from ignition material. In all other respects the construction of the match of Figures 6 to 8 inclusive may be substantially the same as that previously described and shown in Figures 1 to 5 inclusive.

Having thus fully described my invention, what I claim is:

1. A match comprising a splint adapted to be struck endwise against a resistant surface, without rubbing or marring contact, said splint having a head of ignition material thereon at, or near, its striking end, and a train of ignition material extending lengthwise thereon from said head to a point intermediate the ends of the

splint remote from the head, and a holder or finger piece telescoping the other end portion of the splint for sliding movement thereon upon the striking of the splint, and having a frangible connection with the splint normally spacing the inner end of the same from the inner end of the ignition train, the said inner end of the holder having an abrasive movable into frictional engagement with the inner portion of the ignition train upon lengthwise movement of the holder on, and relative to, the splint.

2. An endwise striking match comprising a splint having an ignition head at, or near, its striking end, and an ignition train extending lengthwise thereof and partially therealong from said head, and an abrasive holder forming a finger piece and sleeved on the other end portion of the splint, having a frangible connection with the splint normally fixing the holder in spaced relation to the inner end of the ignition train, said holder having an abrasive at, or near, its inner end.

3. A match comprising a splint adapted to be struck endwise against a resistant surface and having an ignition head at, or near, its striking end, and an ignition train extending lengthwise partially therealong from said head, a finger piece sleeved on the other end portion of the splint having an abrasive at, or near, its inner end to frictionally contact the ignition train, and means frangibly connecting the said finger piece with the splint and normally holding the abrasive of the former in spaced relation to, and from contact with, the ignition train.

4. A match comprising a splint having an ignition head at, or near, one end thereof, a finger piece slidably relatively to the splint at its other end, cooperating means on the splint and the inner end of said finger piece for initiating ignition at a point remote from the ignition head, means for communicating initial ignition from said point to the ignition head, and means normally holding the finger piece in position with the said cooperating means in spaced apart relation lengthwise of the splint.

5. A match comprising a splint having a main ignition head at, or near, one end thereof, a finger piece slidably disposed on the other end portion of the splint, relatively engageable means on the splint and the inner portion of the finger piece for initiating ignition at a point remote from the ignition head upon movement of the finger piece toward the head end of the splint, means normally preventing such movement of the finger piece and maintaining said engageable means in spaced relation, means for communicating initial ignition to the ignition head, and means limiting effective movement of the finger piece toward the head end of the splint.

6. A match comprising a splint having a main ignition head at, or near, one end thereof, a finger piece slidable on the other end portion of the splint, relatively engageable means on the splint and the inner end of said finger piece for initially causing ignition at a point remote from the head and subsequently communicating ignition to the head, means normally holding the finger piece in a position wherein said engageable means are spaced apart, and means limiting effective movement of the finger piece toward the head end of the splint.

ELI E. PENTER.
